VOLTAGE REGULATOR

Michael Debrey, East Moline, Ill.

Application November 30, 1939, Serial No. 306,961

7 Claims. (Cl. 200—91)

The present invention relates to regulators intended particularly for use in controlling alternating current generators.

More specifically it relates to voltage regulators wherein a resistance in series with the field winding of the direct current exciter is intermittently short-circuited so as to keep the field excitation of the alternator supplied from the said exciter at the proper value to maintain the correct output voltage of the alternating current generator.

The invention presents improvements over the voltage regulator of my Patent 2,234,110, March 4, 1941 in which voltage regulation is dependent upon vibratory make-and-break coaction of an arm-carried movable contact with a relatively-fixed, yieldably mounted contact, the arm being actuated in one direction by gravity and in the opposite direction by the core armature of a solenoid to which is applied the voltage to be regulated. That regulator is satisfactory in operation where it is mounted in a perpendicular position on a support not subject to vibration or to tilting movements but is not satisfactory where the regulator is mounted on a movable support such as a boat or truck.

The invention contemplates an alternating current electro-magnet having a winding supplied through a resistor from one of the output circuits of the alternator, an armature pivoted within the field of said electro-magnet, and a contact carried by said armature and cooperating with a relatively stationary contact, said pair of contacts being connected respectively to the terminals of the field rheostat of the exciter, the said electro-magnet preferably having an added air gap in its magnetic circuit to increase the speed of response of said magnet due to the increased reluctance.

The invention contemplates improvements in various details of such regulators, such as means for varying the amplitude of the vibration, means for decreasing the resistance of the air acting on the vibratory member, and means for accurately counter-balancing the vibratory member so as to make the regulator relatively insensitive to variations of position and extraneous disturbances, such as might be encountered when the regulator is mounted on a portable generating outfit, mounted on a vehicle or carried by man or animal.

Other objects and advantages of the invention will in part be stated specifically in the present specification and the drawings accompanying the

same, and in part will be self-evident from the disclosure.

In the accompanying drawings, which diagrammatically illustrate a preferred embodiment of the invention,

Fig. 1 is a diagrammatic elevation showing the structural parts of the instrument and indicating the circuits and electrical devices connected thereto;

10 Fig. 2 is a diagrammatic partly sectional plan view of the instrument itself, certain connections leading thereto also being indicated;

Fig. 3 is a front elevation, partly in section, of the relatively stationary contact and its supporting and adjusting means;

15 Fig. 4 is a side elevation thereof;

Fig. 5 is a front elevation of the vibratory contact with its supporting arm and balance weight; and

Fig. 6 is a side elevation corresponding thereto. It will be noted that Figs. 3, 4, 5 and 6 are drawn to a larger scale than Figs. 1 and 2. In all the figures, similar parts are designated by the same reference characters.

20 Referring specifically to Figs. 1 and 2, it will be seen that the device comprises two sets of laminations 1 and 2 which are held at the proper positions to provide a large gap between the pole faces 3 and 4 to receive the armature 5, said surfaces 3 and 4 being slightly concave to cooperate properly with the ends 6 and 7 of the armature 5, which are correspondingly convex, so that the armature 5 may oscillate about its pivots 8, 9, without striking the pole faces 3 and 4 but nevertheless will move very close thereto.

25 The core sections 1 and 2 at their other ends terminate at 10 and 11, which are spaced apart a suitable distance to introduce a relatively large air gap in the U-shaped core at a point remote from the pole faces 3 and 4. In order to maintain the core sections 1 and 2 in their said positions, frames or plates 12 and 13 preferably of insulating material may be provided, through which pass the bolts 14, said bolts extending

30 through bores 15 in the core sections and through corresponding holes in the plates 12 and 13, tubular spacers 16 being provided to afford proper clearance for the mechanism, and nuts 17 serving to secure the parts firmly in position.

35 A bushing 18 may be secured in the plate 12 by means of a nut 19, and a similar bushing 20 and nut 21 may be provided in the plate 13. A screw 22 having a conical or other suitable bearing cavity 23 in its end may be threaded through the bushing 18 and secured in adjusted position

40

45

50

55

by a lock nut 24 while a screw 25 is similarly threaded through the bushing 20, but need not be provided with a lock nut, since only one of the screws needs to be adjusted. The screw 25 also has a conical or other depression 26 therein and the armature 5 is mounted upon a shaft or spindle 27, whose pointed ends 8 and 9 are mounted to move freely in said cups or cavities.

A spring 28, here shown as helical, surrounds the spindle 27, being secured at one end to a pin or screw 29 on the armature 5, while its other end is similarly secured to a pin 30 carried by a stationary part of the device, here shown as the head or flange of the bushing 18, so that said spring may be adjusted by turning the bushing as a whole, before tightening the nut 13.

A bracket 31 may be secured to the plate 13 by any suitable means, such as the screw 32 and nut 33, and this bracket affords a support for the relatively stationary but vibratory contact. As illustrated, the vertical stem or bracket 34 may have a prolongation 35 extending through a corresponding bore in the bracket 31, a screw 36 serving to retain the support 34 in said bracket 31 in its adjusted position. The upstanding portion of the bracket 34 has a hole 37 near its upper end, through which passes the threaded shank or stem 38 of a member 39 carrying a contact 40, a nut 41 being threaded on the free end of the member 38, with a fiber or other preferably non-metallic washer 42 interposed, as shown. The nut 41 is preferably formed with a tubular extension which receives the shank 38 as shown in Fig. 3.

A spring 43 urges the member 39 away from the arm 34. The spring 43, as well as a reinforcing spring 44, are secured at their lower ends to the corresponding end of the arm 34 by a screw 46, the spring 44 being somewhat shorter than the spring 43 and bearing flatly against the outer side thereof. The spring 44 is very much stiffer than the spring 43 and serves to reinforce and guide the latter, while itself being capable of adjustment by the screws 47 and 48, for short and long contact intervals respectively, said screws being threaded through the member 34. As the member 34 is relatively stationary, it need not be particularly light in weight and may be made large enough to be suitably rigid.

However, the vibrating support 49, which is carried by the armature 5, should have its surface normal to its direction of vibration reduced as much as possible, to keep the resistance of the air as small as possible, so that the damping will not be excessive. This member 49 may therefore suitably be made of sheet metal or the like, preferably bent into channel cross section as shown, and with the web of the channel removed throughout most of its length. It carries a screw-threaded member 50 having a head 51 with a contact 52 thereon, cooperating with the stationary contact 40, a nut 53 serving to secure it in position.

The member 49 is mounted on the shaft 27 and has a screw-threaded shank 54 extending downwardly therefrom, to receive the threaded counterpoise 55, which may be held in adjusted position by the lock nut 56. The armature 5 may be held to the spindle 27 in any desired way, as by a collar 57 and a nut 58 threaded on said spindle.

The electrical connections will now be described.

A winding 60, shown conventionally in Fig. 1 and in diagrammatic plan view in Fig. 2, is arranged over the lower inwardly extending arms

of the core members 1 and 2 and preferably insulated from the same by a suitable tubular member 59. The winding 60 is usually made of relatively fine wire and has a large number of turns, as is customary in voltage coils. One terminal 5 of the coil 60 is connected through conductor 61 to one of the output leads 62, of the alternating current generator 63, while the other terminal 10 of the coil 60 is connected through conductor 64 and resistor 65 to a companion output lead 66 of the said generator, for example, the conductors 62 and 66 may be the sole output terminals of the generator, or one side of a three-wire system, or one of the phases of a multiphase generator, as the case may be.

The field winding 67 of the alternator 63 is connected through conductors 68 and 69 to the brushes 70 and 71 of the direct current generator 72, which serves to excite the field of the alternator. The conductor 68 also extends further and terminates at the member 34, so that it is in electrical connection with the stationary contact 40. The conductor 69 leads to the field winding 73 of the exciter, then through the field rheostat 74 and its sliding contact 75 back to the conductor 68, so that the field excitation of the exciter will be supplied and controlled through said rheostat.

An additional conductor 75 leads from the other terminal of the rheostat, that is, the common terminal of the rheostat and the exciter field winding, to the member 49, the portion 76 of said conductor being of suitable flexibility to offer no great resistance to the vibratory motion of member 49. A capacitance such as a condenser 77 is bridged across conductors 68 and 75, to eliminate sparking between the contacts 40 and 52.

The operation is as follows:

40 When the generating outfit is in service, a relatively small alternating current will flow through the coil 60, under the control of the fixed resistor 65, which restricts the current to a suitable value, proportional to the voltage being produced by the alternator. This current produces an alternating magnetic flux through the core sections 1 and 2 and the armature 5, tending to draw the said armature periodically and synchronously into line with the pole pieces. This produces an oscillatory motion of the armature 5, having a period determined by the frequency of the alternating current coming from the generator, and an amplitude dependent upon the voltage of said current.

55 The contacts 40 and 52 will therefore touch one another periodically and for intervals dependent upon the position of the armature and the amplitude of the vibration. Since the contact 40 is carried by a spring 43, it may yield when the other contact strikes it and thus maintain the connection for a period dependent in part upon the amplitude of vibration, as stated. Whenever such connection exists it is clear that the rheostat 74 will be short-circuited, thereby raising the voltage of the exciter and in turn augmenting the voltage of the alternator to a corresponding extent.

60 Inspection of Fig. 1 will show that when the armature 5 is deflected further in a clockwise direction, the intervals during which contact is made will be relatively shorter than when the armature 5 is not deflected to such a great extent. However, the clockwise motion of the armature corresponds to an increase of flux in the regulator due to an increase of output voltage of the

70 75

alternator so that under these conditions the rheostat 74 will not be short-circuited for as long an aggregate time as when the voltage is lower. In this way, by adjusting the springs 28, 43 and 44 suitably, and also by setting the rheostat contact 78 to the correct position, it will be possible within reasonable limits to maintain the output voltage of the alternator 63 at the desired value.

By adjusting the counterpoise 55 to the correct position on the screw 54, the oscillating system may be made independent of the position of the regulator, much as the balance wheel of a watch is adjusted to operate correctly in any position of the watch, thus making the present regulator well adapted for portable use, where it is not possible to set the apparatus in a correctly leveled position, because of lack of time, or because it is mounted on a moving support such as a vehicle or other carrying device.

It will be noted that the screws 47 and 48 are located at different distances from the screw 46. This affords a greater range of adjustability for the device for tuning the contacts, and while in certain cases either one screw or the other could be omitted, where it is known beforehand what class of service the regulator is to assume, where the device is to be of general use, it is preferable to retain both adjusting screws.

The washer 42 is provided to prevent any undue wear from occurring between the nut 41 and the arm 34. This washer may be made of any suitable material, such as Bakelite, fiber, etc., which will not readily cut the relatively harder metal, of which the member 34 is made.

It will be seen that the armature 5 will tend to take up a mean position corresponding to the mean value of the magnetic flux acting thereon, while nevertheless constantly vibrating slightly, due to the alternating character of said flux. This vibration makes the regulator very sensitive and tends to prevent sticking of the contacts.

While one form of the device has been disclosed in detail, it is obvious that the present specification is to be understood in an illustrative sense and not as a limitation, since the invention may be embodied in many other physical forms. The scope of the invention is therefore defined solely by the following claims.

While the preferred embodiment of the invention herein presented is illustrative of its use in the regulation of the voltage of alternators, the invention may be used also for other purposes within its capabilities.

I claim:

1. In a voltage regulator, the combination of a pivoted member so constructed and mounted as to be oscillated when an alternating magnetic flux is applied directly thereto, an oscillating contact movable with said member and spaced radially outward from its pivot, said member and its contact being dynamically balanced, a relatively stationary but vibratory contact to coact with said oscillatory contact, said contacts being engageable in a vibratory manner, a spring for urging said vibratory contact toward said oscillatory contact, means for limiting the movement of said vibratory contact toward said oscillatory contact under the action of said spring, means to tune said contacts by adjusting said spring, spring means for biasing said member to cause it to assume a definite position for a given flux acting thereon, means to vary the period during which said contacts remain engaged by adjusting said spring means, and means for applying directly to said member an alternating magnetic

flux corresponding to that produced by the voltage to be regulated.

2. In a voltage regulator, the combination of a substantially U-shaped core of magnetic material terminating in opposed concave pole faces, an armature of magnetic material mounted pivotally for oscillation between said pole faces, the ends of the armature being convex to coact with said pole faces, a contact carried by the armature, means for changing the center of gravity of the armature and its contact to dynamically balance the same, a relatively stationary contact to coact with the first mentioned contact, said contacts being engageable in a vibratory manner, a spring for urging the relatively stationary contact toward the first mentioned contact, means for limiting the movement of the relatively stationary contact toward the first mentioned contact, means to tune said contacts by adjusting the tension of said spring, a spring for biasing the armature to cause it to assume a definite position for a given flux acting thereon, means for adjusting the last mentioned spring to vary the period during which the contacts remain engaged, and means comprising a winding on the core to be energized by applying thereto the voltage to be regulated.

3. In a voltage regulator, the combination of a substantially U-shaped core of magnetic material terminating in opposed pole faces, a dynamically balanced armature of magnetic material mounted pivotally for oscillation between said pole faces, a rigid arm movable with the armature and projecting radially in one direction from its pivot, a contact carried by said arm, adjustable means projecting radially from the pivot of said armature to counter-balance said arm and its contact, a relatively stationary contact to coact with the first mentioned contact, said contacts being engageable in a vibratory manner, a spring for urging the relatively stationary contact toward the first mentioned contact, means for limiting the movement of the relatively stationary contact toward the first mentioned contact, means to tune said contacts by adjusting the tension of said spring, a spring connected between the armature and the core for biasing the armature to cause it to assume a definite position for a given flux acting thereon, means for adjusting the last mentioned spring to vary the period during which the contacts remain engaged, and means comprising a winding on the core to be energized by applying thereto the voltage to be regulated.

4. In a voltage regulator, the combination of a pivoted member so constructed and mounted as to be oscillated when an alternating magnetic flux is applied directly thereto, a rigid arm movable with said member and projecting radially in one direction from its pivot, said arm having a portion turned edgewise in the direction of its motion to minimize air resistance, an oscillatory contact carried by said arm, adjustable means projecting radially from the pivot of said member to counter-balance said arm and its contact, a relatively stationary, vibratory contact to coact with said oscillatory contact, said contacts being engageable in a vibratory manner, a spring for urging said vibratory contact toward said oscillatory contact, means for limiting the movement of said vibratory contact toward said oscillatory contact under the action of said spring, means to tune the said contacts by adjusting said spring, spring means for biasing said member to cause it to assume a definite position for a given

flux acting thereon, means to vary the period during which said contacts remain engaged by adjusting said spring means, and means for applying directly to said member an alternating magnetic flux corresponding to that produced by the voltage to be regulated.

5. In a voltage regulator, the combination of a pivoted member so constructed and mounted as to be oscillated when an alternating magnetic flux is applied directly thereto, an oscillatory contact movable with said member and spaced radially outward from its pivot, said member and its contact being dynamically balanced, a stationary support having an opening, a stem reciprocable in said opening and having at one end a stop head and at its other end a vibratory contact to coact with said oscillatory contact, said contacts being engageable in a vibratory manner, a fibre washer on said stem between its head and said support, a spring for urging said vibratory contact toward said oscillatory contact, means to tune said contacts by adjusting said spring, spring means for biasing said member to cause it to assume a definite position for a given flux acting thereon, means to vary the period during which said contacts remain engaged by adjusting said spring means, and means for applying directly to said member an alternating magnetic flux corresponding to that produced by the voltage to be regulated.

6. In a voltage regulator, the combination of a frame including opposed members of insulating material, a shaft bearing carried by one of said members, a rotatably adjustable bushing carried by the other of said members, a shaft bearing carried by said bushing, one of said shaft bearings being adjustable, a shaft rotatable in said bearings, a substantially U-shaped core of magnetic material mounted in the frame and termi-

nating in opposed pole faces, an armature of magnetic material fixed to said shaft and positioned for oscillation between said pole faces, a coil spring surrounding the shaft and having one end anchored to said adjustable bushing and its other end to said armature, a contact carried by the armature, means for changing the center of gravity of the armature and its contact to dynamically balance the same, a relatively stationary contact to coact with the first mentioned contact, a spring for urging the relatively stationary contact toward the first mentioned contact, means for limiting the movement of the relatively stationary contact toward the first mentioned contact, said contacts being engageable in a vibratory manner, means to tune said contacts by adjusting the tension of the last mentioned spring, and means comprising a winding on the core to be energized by applying there-to the voltage to be regulated.

7. An improvement in a voltage regulator of the type in which voltage regulation is dependent upon vibratory make-and-break coaction of an arm-carried movable contact with a relatively fixed, yieldably mounted contact, the make-and-break movements of the carrying arm of said movable contact being produced by an armature moved in one direction by an alternating magnetic flux and in the opposite direction by gravity; said improvement comprising a single rigid pivotally-mounted and dynamically-balanced oscillating unit which includes both the armature and the contact-carrying arm, whereby said make-and-break coaction of said contacts will not be affected by gravity or by shocks in various directions when the regulator is tilted or subjected to vibration.

MICHAEL DEBREY.
